(57) CLAIM

The ornamental design for a heel portion of a shoe, as shown and described.

DESCRIPTION

FIG. 1 is a rear lateral perspective view of a heel portion of a shoe showing my new design;

FIG. 2 is a lateral side view thereof;

FIG. 3 is a medial side view thereof; and,

FIG. 4 is a rear view thereof.

The broken line showing of the remainder of the shoe is for illustrative purposes only and forms no part of the claimed design.

1 Claim, 4 Drawing Sheets

FIG. 4
